Primary Examiner — Cynthia M Chin*(74) Attorney, Agent, or Firm* — Fulwider Patton LLP;
Jacob S. Zodieru(57) **CLAIM**

The ornamental design for a toy gun, as shown and described.

DESCRIPTION

FIG. 1 is a right side perspective view of a toy gun showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front side elevational view thereof; and,

FIG. 7 is a rear side elevational view thereof.

The features shown in broken lines within the barrel of the toy gun illustrate ornamentation and/or features that form no part of the claimed design.
